CLAIM

The ornamental design for a removable auditory prosthesis interface, as shown and described.

DESCRIPTION

FIG. 1 is a perspective view of a removable auditory prosthesis interface on a headband, showing our new design. FIG. 2 is a perspective view of the removable auditory prosthesis interface of FIG. 1.

FIG. 3 is a front elevation view of the removable auditory prosthesis interface of FIG. 1.

FIG. 4 is a rear elevation view of the removable auditory prosthesis interface of FIG. 1.

FIG. 5 is a left elevation view of the removable auditory prosthesis interface of FIG. 1.

FIG. 6 is a right elevation view of the removable auditory prosthesis interface of FIG. 1.

FIG. 7 is a top plan view of the removable auditory prosthesis interface of FIG. 1; and,

FIG. 8 is a bottom plan view of the removable auditory prosthesis interface of FIG. 1.

The broken lines immediately adjacent the shaded areas represent the bounds of the claim, while all other broken lines are directed to environment and are for illustrative purposes only. The broken lines form no part of the claimed design.

1 Claim, 3 Drawing Sheets
